UNITED STATES PATENT OFFICE.

CORNELIUS THEODORE CAIN, OF OWENSBOROUGH, KENTUCKY.

PHOTOGRAPH TRANSFERRING AND PRINTING FRAME.

SPECIFICATION forming part of Letters Patent No. 398,941, dated March 5, 1889.

Application filed June 15, 1888. Serial No. 277,231. (No model.)

To all whom it may concern:

Be it known that I, CORNELIUS THEODORE CAIN, of Owensborough, in the county of Daviess and State of Kentucky, have invented 5 a new and useful Improvement in Combined Photograph Transferring and Printing Frames, of which the following is a full, clear, and exact description.

The frame which is the subject of this invention is more particularly designed to be used in the process of producing and transferring picture-films to celluloid sheets, as described in Letters Patent No. 368,223, granted to William A. McGill, conjointly with myself 15 as assignee, August 16, 1887. This process consisted in preparing a picture-film or transparency by the collodio-chloride or by the ordinary wet-collodion process, in toning and fixing the picture-film, drying the same, and 20 in applying thereto a celluloid card that has been flowed with a solution of gum-camphor and alcohol, allowing the card to dry, and stripping it from the glass.

My invention consists in a novel construction of the frame with its attachments, substantially as hereinafter described, and pointed out in the claims, said frame being more particularly designed for transferring from the transparency to the celluloid card or plate, 30 but also being applicable to printing photographs and to the mounting of the picture; also, the same may be used as a developing-tray under different processes.

Reference is to be had to the accompanying drawings, forming a part of this specification, in which similar letters of reference indicate corresponding parts in all the figures.

Figure 1 represents a face view of the frame as in use for making the transfer. Fig. 2 is 40 a rear view of the same; Fig. 3, a face view of the frame empty and with its clamping devices removed, and Fig. 4 a rear view of the same. Fig. 5 represents a vertical longitudinal section of the frame in position before applying the transparency to the celluloid card or plate; Fig. 6, a similar section upon the line $x-x$ in Fig. 1, showing the frame in position and as in use for making the transfer; Fig. 7, a like section upon the line $y-y$ in 45 Fig. 1, showing the frame as used for mounting the picture; and Fig. 8, a further longitudinal section similar to Fig. 7, showing the

frame as in use for making a print. Fig. 9 is a transverse vertical section upon the line $z-z$ in Fig. 1. 55

A is the frame proper, of rectangular form and recessed in its rear, as at b, for reception of the various plates and clamping-board, and having a ledge, c, arranged as a lining along its inner sides, preferably made 60 to project slightly above the front surface of the frame to form a trough, which is provided with a spout, d, for running off the solution used in preparing the celluloid plate or card.

B is the clamping-board in the rear, which 65 is faced with a sheet of rubber or other cloth, e, and has centrally pivoted to its back, as at f, a turn-buckle spring-bar, C, that, when the clamping-board is fitted to its place, is sprung to enter at its ends within or on the inside of 70 clips g g, secured to opposite sides of the frame at its back to hold the celluloid plate firmly in position when making the transfer and for otherwise securing the plates entered within the recess b and to make a close joint 75

with the trough as formed by the ledge c, the inner or lower edge of which projects below the top of the recess b for the purpose. The clamping-board B is also provided with pivoted hook-shaped cams D D in its rear on opposite sides and near opposite ends of the spring-bar C. These pivoted cams D D are made beveling at their outer or free ends to enter between the board B and spring-bar C when the latter is in engagement with its 80 clips g g, whereby said cams act as wedges to give increased tension to the spring-bar and to lock or hold it when engaged with its clips. Upon swinging these locking-cams D D back or out, however, from the spring-bar, then 85 said spring-bar may readily be turned or relieved from its engagement with the clips g g to remove the clamping-board and plates from the frame.

A spring clamping device is also applied to 90 the front of the frame to hold the glass or transparency firmly down to its place when making the transfer onto the celluloid plate or card, or whenever it otherwise may be necessary. This clamping device is adjustable up 100 or down, to suit different thicknesses of the glass or plate or plates within the frame and to give any desired pressure. Thus it consists in part of spring-racks E E, attached to

opposite sides of the frame, and in part of a central cross-bar, F, carrying on its under side arms *i i*, to which are secured partially-elliptic springs G G, that bear down upon the 5 glass or plate beneath them when said bar F, which is made with strap-like ends, is fitted over the spring-racks E E, so as to engage with any one of their ratchet-shaped teeth, according to the adjustment required. The 10 spring-racks E E exert a tendency or tension to hold the cross-bar F in lock with them, but easily yield toward each other when fitting said bar over them; or they may be readily pressed by the finger and thumb toward each 15 other when it is desired to remove the bar F and take off spring-pressure from the front side of the frame.

The frame A is also fitted on its front side at what will be termed its "bottom end" with 20 a spring-pressure device, H, having a soft or rubber bearing-block, *k*, to hold the transparency in position on the celluloid plate before clamping it down. At the opposite, or what will be termed the "upper," end of the 25 frame A, or end opposite to that carrying the spout *d*, is a pivoted leg, I, that may be turned down to hold the frame in an inclined position to keep the solution at the bottom preparatory to putting the glass plate down, but 30 which, when not required to be used, may be turned up out of the way alongside the frame.

To transfer the collodion film from the glass or transparency after the same has been suitably prepared and finished, the celluloid 35 plate *l* is inserted to its place within the frame and the rear clamping-board, B, secured by the devices hereinbefore described to hold it there, and so that it forms a close joint with the lower edge of the ledge *c*, the bar F of 40 the front clamping device being removed. The necessary solution is then flowed over the celluloid plate to prepare it, and the frame A set inclining by its leg I, as shown in Fig. 5, to keep the solution at the bottom preparatory to laying the transparency or glass positive *m* down on the celluloid plate *l* and clamping it thereon by the bar F and springs G G, as shown in Fig. 6, the spring-pressure device H serving to hold the glass till the 45 clamping devices have been applied to it and to aid in properly laying the glass down. The spout *d* serves to run off surplus or remaining solution by suitably tipping the frame. After the transfer has been made onto the celluloid

55 card or plate *l* it may be removed from the frame and allowed to dry. If necessary to mount it, the same is inserted in the frame with a mount, *n*, either of thicker suitably-prepared celluloid or card-board at its back and with a glass-presser, *o*, on its top, to which 60 pressure may be applied by the bar F and springs G G, as shown in Fig. 4; or the frame may similarly be used for mounting other kinds of photographic pictures, or it may be used for making photographic prints—as, for 65 instance, by introducing a cloth, *r*, onto the clamping-board B, then over it a suitably-prepared printing-paper or material, *s*, and on top of it the negative *u*, as shown in Fig. 8. The trough-like character of the frame 70 also provides for it being used as a developing-tray, if desired.

Having thus described my invention, what I claim as new, and desire to secure by Letters Patent, is—

75

1. The frame A, having a groove or recess, *b*, in its rear on its inner side and provided with a lining-like strip or ledge, *c*, having its 80 facial sides in direction of the thickness of the frame from front to back and arranged to project below the top wall of the recess in the frame, substantially as specified.

2. The frame A, grooved or recessed in its rear, and provided with a lining-like marginally-projecting ledge, *c*, and spout *d*, essentially as shown and described.

85

3. The frame A, grooved or recessed in its rear, and provided with a lining-like marginally-projecting ledge, *c*, and pivoted leg I at its one end or side, substantially as specified.

90

4. The combination, with the frame A, having a recess, *b*, in its rear, of the clamping-board B, the swiveling spring-bar C, clips *g*, and the pivoted wedge-like cams D D, essentially as described.

95

5. The combination, with the frame A, of the spring-pressure device H *k*, applied to the one or lower end portion of the frame in front, substantially as specified.

6. The combination, with the frame A, of the spring-racks E E, the cross-bar F, constructed to engage with said racks, and the springs G G, carried by said bar, essentially as described.

100

CORNELIUS THEODORE CAIN.
